UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING APPARATUS.

Application filed March 24, 1924, Serial No. 701,390. Renewed July 6, 1927.

My invention relates to mining apparatus.

It has for its object to provide an improved mining apparatus especially adapted to use in entry or room cutting where it is desirable for the machine to operate from its truck. A further object of my invention is to provide an improved swinging mechanism for such a machine whereby the cutter bar may be swung at different desired speeds relative to the work during movement to or from cutting position or during cutting. A still further object of my invention is to provide improved truck driving mechanism and more particularly an improved truck driving mechanism especially adapted to a machine of this type and to a machine having thereon my improved bar swinging mechanism above mentioned. These and other objects and advantages of my invention will hereinafter more fully appear.

In the accompanying drawings I have shown for purposes of illustration one form which my inventions may assume in practice.

In these drawings,—

Fig. 1 is a plan view of a mining apparatus constructed in accordance with my improvement, certain portions being broken away to facilitate illustration.

Fig. 2 is a side elevation of the same apparatus.

Fig. 3 is an enlarged detail of the rear end of the machine and its swinging mechanism, certain portions being shown in vertical section.

Fig. 4 is a detail sectional view of the clutch mechanism.

Fig. 5 is a diagrammatic view showing the machine as used in circular cutting.

Fig. 6 is a similar view showing the machine operating in accordance with the Arc-wall method.

In this illustrative construction I have shown a machine of the general character described and claimed in my copending application Ser. No. 508,390 filed Oct. 17, 1921, including generally a wheeled truck 1 adapted to run over a mine track and carrying thereon an adjustable body section 2 vertically adjustable by hand adjusting means, generally designated 3, in such manner that the section 2 is maintained in parallelism with the track-way in its different elevated positions, although obviously such a construction is not necessary. Upon this body 2 is also carried a complete bottom cutting mining machine 4

which may be of any suitable type, but is herein of a well known chain fed room and pillar type having a reversible electric motor (not shown) and a projecting cutter bar 5, this machine herein being swivelled on the body 2. As shown, the latter also carries suitable truck wheel driving mechanism 6, detachable machine locking mechanism 7, and cable reel mechanism 8, while the mining machine is connected for swinging relative to its swivel and for driving a gear 9 of the truck driving mechanism 6, all in an improved manner hereinafter described.

Referring more particularly to my improved construction it will be noted that the mining machine 4 is fixed to the bottom thereof as by screws 10, a depending guard 11 having an axial portion 12 seated in the bottom of the mining machine and a depending larger axial bearing 13 rotatable in a large spur gear 14 fixed as by bolts 15 to a part 16 carried on the body 2 as will hereinafter be described, a plate 17 held in place by screws acting to retain the member 13 in the desired relation to the stationary gear and other suitable bearings 18 of larger diameter than the bearing 13 also being provided between the member 11 and the stationary gear 14. Moreover, it will be noted that this stationary gear 14 is of substantial diameter (see Fig. 1), and that it meshes at a point near the rear of the machine with a much smaller gear 19 journaled on an axis 20 suitably carried upon the bottom of the machine. This gear 19 in turn meshes with a still smaller gear 21 similarly journaled on a parallel axis 22 and carrying above it, a larger gear 23 which in turn meshes with a spur pinion 24 fixed on the lower end of a driving shaft 25 extending vertically upward and connectible by a clutch 26 of any suitable type, herein shown in detail in Fig. 4, with a chain sprocket 27, the construction being such that when the clutch 26 is thrown in the sprocket 27 acts as a driving sprocket driving the shaft, while when the clutch is thrown out, the sprocket 27 acts as an idler sprocket. More particularly it will be noted that the sprocket 27 is engaged by the feed chain 28 of the machine which is in turn driven by a feed operating member or sprocket 29 rotatable as usual in such machines through feeding mechanism (not shown) at a fast speed in one direction or at a slow speed in the other direction, the feed chain being disposable rel-

ative thereto and the sprocket 27 and cooperating lateral guide sprockets 30, 31 and abutments 32, 33, 34 in a well known manner.

Referring more particularly to the truck driving mechanism, it will be noted that the usual truck driving gear 35 of such a machine here meshes with a spur gear 36 journaled in suitable bearings around the upper end of the shaft 25, and below the member 27 and that this gear 36 in turn is adapted to mesh with the gear 9 of the truck driving mechanism in such manner as to provide power for the propulsion of the wheels of the truck 1 which are as in a usual construction connected to the latter mechanism. More particularly, it will be noted that this truck driving gear 9 will be constantly rotated by the gears 35 and 36 when the gears 36 and 9 are in mesh and that control of truck movement is effected through a friction mechanism operated by a controlling member 37 in a usual manner. The above mentioned part 16 to which the gear 14 is secured is slidably mounted in guides 38 with which clamping members 39, also attached to the part 16 are engageable. It will therefore be understood that during cutting with such a machine as that disclosed, it is initially moved forward bodily in the guides 38 on the truck body 2 to a limited extent and that the clamps 39 are then clamped into position, the gears 36 and 9 thus being out of mesh during the swinging movement of the machine during cutting.

In the operation of my improved machine, when for example it is making a cut of the type shown in Fig. 5, the chain 28 is first fixed to a suitable point in advance of the machine, as a jack or the end of the truck, and the whole machine 4 with its connected parts is then moved forward on the guides 38 to the desired amount to permit the gears 36 and 9 to clear one another, the clamps 39 then being set. Then by simply connecting the chain 28 to an abutment 32 as indicated and the feed, preferably the usual fast feed, power is transmitted to the feed operating member 29 in such manner as to make it draw in the chain and thereby cause the machine to be swung quickly about its swivel or bearing 13 from the longitudinal position shown in Fig. 1 to the lateral position shown in full lines in Fig. 5. The motor is run during this operation in a direction opposite to its direction during cutting. When the bar is in this position, by again connecting the chain to a suitable abutment in front of the machine, the machine is then suitably advanced bodily toward the face on the rails in such manner as to assure that the bar will cut to the maximum depth. Then, after the machine has been fixed in that position as by jacks 40 or other suitable means and the chain has preferably been disconnected, the gear feed controlling clutch 26 is first connected, the slow feed being used, whereupon the gear 19 will be operated

through its various connected gears not only at a much slower speed due to the slow feed gearing of the machine per se, but also due to the reduction inherent in the compound gearing hereinabove described as carried on the truck, in such manner that the tip of the bar which is doing the cutting, which would otherwise travel too rapidly, is moved at the desired cutting speed, the same travelling through an arc of 180° or more to cut out an arcuate kerf such as indicated in dotted lines in Fig. 5. To hold the machine in its angular position during the sumping and withdrawing cuts any suitable means may obviously be employed. Obviously this operation may be repeated in another entry or room while the coal is being removed in the room or entry just cut. In preparing for transport it will also be evident that by suitably reversingly connecting the chain, as indicated in dotted lines, and operating the fast feed, the machine may be swung back to its longitudinal position, whereupon, following a release of the clamping means 39 and a suitable connection of the chain 28 to a usual abutment 34 carried on the rear end of the truck, the machine may be moved bodily backward on the guides 38 to bring the gears 36 and 9 into mesh and enable the lock 7 to be set, the machine being then ready for transport to another place as soon as the jacks 40 are released and placed in their transport position on the truck. Similarly, when it is desired to operate the machine as shown in Fig. 6, the bar is first swung laterally into the full line position shown on the fast feed and then by suitably connecting the feed chain as illustrated and using the slow feed, the whole machine is moved forward until the bar assumes the upper dotted line position illustrated, whereupon the machine then being fixed relative to the track, the bar is similarly swung at its slow speed and through the clutch 26 and gearing 19 etc. to cut out the kerf indicated, i. e. until it reaches the left hand bottom dotted line position indicated. Obviously, by again suitably connecting the feed chain and using the slow feed, the whole machine may be moved rearward to finish the cut, i. e. until the bar occupies the right hand bottom dotted line position, whereupon the machine may be prepared for transport as previously described. It will also be evident that by reversely receiving the chain in a well known manner a reverse operation of the gearing may be obtained, the abutment 33 then being used in the fast swinging.

As a result of my improved construction it will be observed that the tip of the machine bar is adapted to be moved at a slow speed adapting it for cutting rather than at the higher speed which, by reason of the distance between the tip of the bar and the machine axis, would otherwise result if the bar was swung at the same speed as the slow feed

of the machine, per se. At the same time, it will be noted that the machine may be angled rapidly whenever desired by connecting the feed chain to suitable abutments and utilizing the fast feed. Moreover, it will be observed that the mechanism is exceedingly simple and rugged and adapted to be applied to a standard mining machine with slight change therein. These and other advantages 10 of my improved construction will, however, be clearly apparent to those skilled in the art.

While I have in this application specifically described one form which my invention 15 may assume in practice, it will be understood that this form of the same is shown for purposes of illustration and that the invention may be modified and embodied in various other forms without departing from its spirit 20 or the scope of the appended claims.

What I claim as new and desire to secure by Letters Patent is:

1. In a mining apparatus, a support, a mining mechanism horizontally swingable 25 thereon and having slow speed feeding mechanism, and swinging mechanism driven by the terminal element of said feeding mechanism and including supplemental reduction mechanism.
2. In a mining apparatus, a truck, a mining machine horizontally swingable thereon and having slow speed feeding mechanism, and swinging mechanism driven by the terminal element of said feeding mechanism 35 and including supplemental reduction mechanism having an element coaxial with the machine axis.
3. In a mining apparatus, a truck, a mining machine horizontally swingable thereon and having slow speed feeding mechanism, and swinging mechanism driven by the terminal element of said feeding mechanism and including supplemental reduction mechanism having an element fixed to said truck 45 and coaxial with the machine axis.
4. In a mining apparatus, a truck, a mining machine horizontally swingable thereon and having slow speed feeding mechanism, and swinging mechanism driven by the terminal element of said feeding mechanism and including supplemental reduction mechanism having an element coaxial with the machine axis and cooperative elements movable relative thereto with the machine.
5. In a mining apparatus, a truck, a mining machine horizontally swingable thereon and having slow speed feeding mechanism, and swinging mechanism driven by the terminal element of said feeding mechanism 60 and including supplemental reduction mechanism having an element fixed to said truck and coaxial with the machine axis and cooperative elements movable relative thereto with the machine.
6. In a mining apparatus, a truck, a flex-

ibly fed mining machine horizontally swingable thereon and including feed operating mechanism including a flexible feeding member, and swinging mechanism between said machine and truck operated by said feed operating mechanism.

7. In a mining apparatus, a truck, a flexibly fed mining machine horizontally swingable thereon and including feed operating mechanism, and swinging mechanism between said machine and truck operated by the flexible feeding member of said machine and including final transmission means between said flexible feeding member and said truck.

8. In a mining apparatus, a truck, a flexibly fed mining machine horizontally swingable thereon and including feed operating mechanism, and swinging mechanism between said machine and truck operated by the flexible feeding member of said machine and including an idler for the latter and a clutch controlling the connection of said idler.

9. In a mining apparatus, a truck, a mining machine movable longitudinally of said truck, a swivel for said machine as a whole and movable longitudinally therewith, and swinging mechanism driven by said machine and including an element coaxial with said swivel.

10. In a mining apparatus, a truck, a mining machine movable longitudinally of said truck, a swivel for said machine as a whole and movable longitudinally therewith, and swinging mechanism driven by said machine and including reduction mechanism having an element coaxial with said swivel.

11. In a mining apparatus, a truck, a horizontally swingable mining machine thereon having a flexible feeding member and fast feed mechanism for swinging said machine rapidly, and a plurality of cooperating slow feed mechanisms one actuating said flexible feeding member and the other actuated thereby for swinging the machine slowly.

12. In a mining apparatus, a truck, mining mechanism horizontally swiveled thereon including a flexible feeding member and fast and slow feed mechanism therefor, operative connections for enabling swinging of said mining mechanism with said flexible feeding member and the fast feed, and operative connections for swinging the same at a feed slower than the slow feed.

13. In a mining apparatus, a truck, a mining mechanism horizontally swiveled thereon including a flexible feeding member and fast and slow feed mechanism therefor, operative connections for enabling swinging of said mining mechanism with said flexible feeding member and the fast feed, and operative connections for swinging the same at a feed slower than the slow feed and in a reverse direction from the fast feed.

14. In a mining apparatus, a truck, a min-

ing mechanism horizontally swiveled thereon including a flexible feeding member and fast and slow feed mechanism therefor, operative connections for enabling swinging of said machine with said flexible feeding member and the fast feed, and operative connections for swinging said machine at a feed slower than the slow feed, said connections including driving and driven elements connected by 10 said flexible member.

15. In a mining apparatus, a truck, a mining mechanism horizontally swiveled thereon including a flexible feeding member and fast feed mechanism therefor, operative connections 15 for enabling swinging of said mining mechanism with said flexible feeding member and the fast feed, and operative connections for swinging said machine at a slow feed, said connections including driving and driven elements 20 connected by said flexible member and a clutch controlling the connection of the driven element.

16. In a mining apparatus, a truck, a mining mechanism horizontally swiveled thereon including a flexible feeding member and fast feed mechanism therefor, operative connections 25 for enabling swinging of said mining mechanism with said flexible feeding member and the fast feed, and operative connections 30 for swinging said machine at a slow feed, said connections including driving and driven elements connected by said flexible member, a clutch controlling the connection of the driven element, and gearing driven by said 35 driven element and disposed between said mining machine and truck.

17. In a mining apparatus, a truck, a mining mechanism horizontally swiveled thereon including a flexible feeding member and fast 40 feed mechanism therefor, operative connections for enabling swinging of said mining mechanism with said flexible feeder member and the fast feed, and operative connections 45 for swinging said machine at a slow feed, said connections including driving and driven elements connected by said flexible member, a clutch controlling the connection of the driven element, and gearing driven by said 50 driven element and disposed between said mining mechanism and truck in horizontal planes.

18. In a mining apparatus, a support, a mining mechanism swiveled thereon and having a feed operating member, a flexible feeding 55 member cooperating with the latter, an idler member engaged by said flexible member, and swinging mechanism operatively connectible to said idler member.

19. In a mining apparatus, a support, a mining mechanism swiveled thereon and having a feed operating member, a flexible feeding member cooperating with the latter, an idler member engaged by said flexible member, and swinging mechanism operatively 65 connectible to said idler member including a

clutch controlling the connection of said latter member.

20. In a mining apparatus, a support, a mining mechanism swiveled thereon and having a feed operating member, a flexible feeding member cooperating with the latter, an idler member engaged by said flexible member, and swinging mechanism operatively connectible to said idler member including a clutch controlling the connection of said latter member and driving gearing controlled by said clutch. 70

21. In a mining apparatus, a support, mining mechanism horizontally swingable thereon and including cutting mechanism, a motor driving the cutting mechanism, and feed mechanism driven by said motor for bodily feeding said mining mechanism as a whole, and swinging mechanism for said mining mechanism as a whole driven by said feed mechanism. 80

22. In a mining apparatus, a support, mining mechanism horizontally swingable thereon and including cutting mechanism, a motor driving the cutting mechanism, and feed 90 mechanism driven by said motor for bodily feeding said mining mechanism as a whole, and swinging mechanism for said mining mechanism as a whole driven by said feed mechanism and including supplemental reduction means. 95

23. In a mining apparatus, a support, mining mechanism horizontally swingable thereon and including cutting mechanism, a motor driving the cutting mechanism, and feed mechanism driven by said motor for bodily feeding said mining mechanism as a whole, and swinging mechanism for said mining mechanism as a whole driven by said feed mechanism and including supplemental reduction means having an element coaxial with the axis of swing of the machine. 100

24. In a mining apparatus, a support, mining mechanism horizontally swingable thereon and including cutting mechanism, a motor driving the cutting mechanism, and feed mechanism driven by said motor for bodily feeding said mining mechanism as a whole, and swinging mechanism for said mining mechanism as a whole driven by said feed 110 mechanism and including supplemental reduction means having an element fixed to the truck and coaxial with the axis of swing of the machine. 115

25. In a mining apparatus, a support, mining mechanism horizontally swingable thereon and including cutting mechanism, a motor driving the cutting mechanism, and feed mechanism driven by said motor for bodily feeding said mining mechanism as a whole, and swinging mechanism for said mining mechanism as a whole driven by said feed mechanism and including supplemental reduction means having an element coaxial with the axis of swing of the machine and co- 120 125 130

operating elements movable relative thereto with the machine.

26. In a mining apparatus, a support, mining mechanism horizontally swingable thereon and including cutting mechanism, a motor driving the cutting mechanism, and feed mechanism driven by said motor for bodily feeding said mining mechanism as a whole, and swinging mechanism for said mining mechanism as a whole driven by said feed mechanism and including supplemental reduction means having an element fixed to the truck and coaxial with the axis of swing of the machine and cooperating elements movable relative thereto with the machine.

27. In a mining apparatus, a support, a mining mechanism supported thereon for horizontal swinging movement and for vertical adjustment relative to said support, said mining mechanism having slow speed feeding mechanism therefor vertically adjustable therewith, and swinging mechanism driven by said feeding mechanism and including supplemental reduction mechanism.

28. In a mining apparatus, a truck, a mining machine supported thereon for horizontal swinging movement and for vertical adjustment and having slow speed feeding mechanism therefor vertically adjustable therewith, and swinging mechanism driven by the terminal element of said feeding mechanism and including supplemental reduction mechanism having an element coaxial with the machine axis.

29. In a mining apparatus, a truck, a mining machine supported thereon for horizontal swinging movement and for vertical adjustment and having slow speed feeding mechanism therefor vertically adjustable therewith, and swinging mechanism driven by the terminal element of said feeding mechanism and including supplemental reduction mechanism having an element fixed to said truck and coaxial with the machine axis.

30. In a mining apparatus, a truck, a mining machine supported thereon for horizontal swinging movement and for vertical adjustment and having slow speed feeding mechanism therefor vertically adjustable therewith, and swinging mechanism driven by the terminal element of said feeding mechanism and including supplemental reduction mechanism having an element coaxial with the machine axis and cooperating elements movable relative thereto with the machine.

31. In a mining apparatus, a truck, a mining machine supported thereon for horizontal swinging movement and for vertical adjustment and having slow speed feeding mecha-

nism therefor vertically adjustable therewith, and swinging mechanism driven by the terminal element of said feeding mechanism and including supplemental reduction mechanism having an element fixed to said truck and coaxial with the machine axis and cooperating elements movable relative thereto with the machine.

32. In a mining apparatus, a wheeled support, a mining machine adjustably mounted thereon and including cutting mechanism, a motor driving said cutting mechanism, and flexible feeding mechanism driven by said motor including a flexible feeding element, and mechanism including cooperating elements on said machine and support driven by said feeding mechanism for adjusting said mining machine relative to said support to change the position of said cutting mechanism.

33. In a mining apparatus, a wheeled support, a mining machine adjustably mounted thereon and including cutting mechanism, a motor driving said cutting mechanism, and flexible feeding mechanism driven by said motor including a feed operating member and a cooperating flexible feeding element, and mechanism including cooperating elements on said machine and support operated by said flexible element for adjusting said mining machine relative to said support to change the position of said cutting mechanism.

34. In a mining apparatus, a wheeled support, a mining machine adjustably mounted thereon and including cutting mechanism, a motor driving said cutting mechanism, and flexible feeding mechanism driven by said motor including a feed operating member and a cooperating flexible feeding element, and mechanism operated by said flexible element for adjusting said mining machine relative to said support to change the position of said cutting mechanism, said adjusting mechanism including supplemental reduction means.

35. In a mining apparatus, a wheeled truck, a swivel guided on and movable longitudinally of said truck, a mining machine mounted for horizontal swinging movement on said swivel and including cutting mechanism, a motor driving said cutting mechanism and feeding mechanism driven by said motor, all swinging together and swinging mechanism for said machine driven by said feed mechanism including a final positively geared transmission constituting speed reduction means.

In testimony whereof I affix my signature.

MORRIS P. HOLMES.

CERTIFICATE OF CORRECTION.

Patent No. 1,704,668.

Granted March 5, 1929, to

MORRIS P. HOLMES.

It is hereby certified that error appears in the printed specification of the above numbered patent requiring correction as follows: Page 2, lines 77 to 80, strike out the paragraph "To hold the machine in its angular position during the sumping and withdrawing cuts any suitable means may obviously be employed" and insert the same to follow after the word "described" in line 118; same page, line 119, for the word "receiving" read "reeving"; and that the said Letters Patent should be read with these corrections therein that the same may conform to the record of the case in the Patent Office.

Signed and sealed this 23rd day of April, A. D. 1929.

(Seal)

**M. J. Moore,
Acting Commissioner of Patents.**
